SEALING MEANS FOR CONTAINERS

Filed Aug. 11, 1924

FIG. 1

FIG. 2

INVENTOR
John M. Hothersall
BY *Munday*,
Clarke & Carpenter
ATTORNEY

UNITED STATES PATENT OFFICE.

JOHN M. BOTHERSALL, OF BROOKLYN, NEW YORK.

SEALING MEANS FOR CONTAINERS.

Application filed August 11, 1924. Serial No. 731,267.

This invention relates in general to closing means for containers, and has for a primary object the provision of a seal usable, for example, upon a pouring spout, or the 5 end of a collapsible tube, and comprising an integral part of the spout extended over the end of a dispensing opening and severable by means of a knife, or like instrument, when it is desired to use the contents of the container.

10 Numerous other objects and advantages of the invention will be apparent as it is better understood from the following description, which, taken in connection with the accompanying drawings, discloses a preferred embodiment thereof.

Referring to the drawings,

Figure 1 is a vertical section of a pouring spout provided with sealing means embodying my invention and showing the removable 20 cap in place;

Fig. 2 is a similar view, showing the sealing part severed from the end of the spout and the cap in separated relationship.

Upon the drawings, which illustrate the 25 best manner in which I have contemplated applying the principles of my invention, the applying the principles of my invention, the reference character 21 indicates a spout or outlet member which is formed of relatively soft, 30 easily severable material, such as lead, or an amalgamation of metals resulting in soft metal, and is provided with a dispensing tube, passage or opening 22. The spout, in the present instance, is of tapered form, the opening, or 35 tube 22 narrowing toward the top and being closed by means of a sealing part 23 which is integral with the spout wall and is extended over the end of the opening. This part is adapted to be severed by means of a knife, 40 or other appropriate instrument, when it is desired to make use of the contents of the container, and it will be apparent that prior to this time a perfect hermetic seal is provided, 45 there being no opportunity for evaporation or leakage of the contents. This is highly important when the container upon which the spout is used is employed for certain grades of oil, or other volatile liquids, and it is contemplated also that a seal may be advantageously used in connection with collapsible 50 tubes containing a semi-liquid in which evaporation is to be particularly avoided.

The upper part of the spout is exteriorly threaded at 24 and formed with a conical portion 25 between the threads and the sealing 55 part 23. A cap or closure 26, having internal threads 27, is adapted to fit upon the end of the spout and is provided with an interior shoulder or sealing projection 28, which is brought into tight engagement with the conical part 60 25 of the spout when the cap is screwed down, thus providing a metallic seal or reclosure preventing evaporation or leakage of the contents after the sealing part 23 has been severed.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A container, comprising an outlet part of soft metal, having a conical portion at the outer end thereof, and a cap adapted to be tightened upon said part, and having an 80 angular shoulder adapted to be forced into sealing engagement with said conical portion thereof.

2. A container, comprising an outlet part of soft metal, having a conical portion at the 85 outer end thereof terminating in an integral sealing tip of cylindrical form and severable from said conical portion by a knife or like instrument for opening the container, and a cap adapted to be tightened upon said part 90 and having a shoulder adapted to be forced into sealing engagement with said conical portion thereof.

3. A lead pouring spout adapted to be opened by cutting, which consists of a lead 95 body formed at its forward end with a conical portion, and with a screw thread, and with a forward cylindrical extension terminating in a sealing part which is relatively thick and solid, all of said parts being formed in one 100 piece of lead, and a screw threaded cap screwed on the end of the spout and provided with an interior shoulder adapted to bear on the conical surface to close the spout after it

has been cut, the spout being openable by cutting across the cylindrical part at the inner side of said thickened sealing part.

4. A container spout, comprising a screw threaded outlet member of soft metal and a screw threaded closure member adapted to engage the screw threads of said outlet member,

and coacting parts on said members, comprising a cone on the spout and an angular shoulder on the cap, for producing a biting metal 10 to metal sealing engagement between said members when said closure member is fully applied.

JOHN M. HOTHERSALL.
